PAPER DRINKING CUP

Louis V. Lucia, West Hartford, Conn., assignor to
Lucup Corporation, a corporation of New
York

Application May 8, 1935, Serial No. 20,383

4 Claims. (Cl. 229—53)

This invention relates to that class of paper drinking cups which are intended to be used once and then discarded. It is very evident that cups of this class must necessarily be of such form that they can be manufactured in a most economical manner.

It is preferred to have cups of this type of a substantially tapered form in order that the cup may be more readily grasped in the hand of the user and held with less pressure on the cup than is required to hold a cup which is not tapered.

The method now commonly used in producing cups, and especially those of such tapered form, consist of first cutting out blanks from a stack 10 of paper sheets, then placing a stack of blanks in a machine which picks up one at a time, by means of a suction device, and forms them into cups.

In producing cups in this manner the operation is necessarily slow and the equipment required is very costly as it is necessary to have air pumps in connection with the forming machine and also large presses for cutting out the blanks.

25 The object of my invention is to construct a paper drinking cup in such a manner that it can be formed from a substantially square blank which may be cut from a web of paper that is supplied to a forming machine from a roll; the 30 operation of cutting a blank from the web serving at the same time to trim the blank so as to give it the proper form with a minimum of waste.

35 A further object of my invention is to provide a drinking cup which, when folded, has sufficient overlap to prevent leakage of water therefrom and is sufficiently reinforced in a manner which will render it of maximum rigidity.

40 Further objects of my invention can be clearly understood from the following description and the drawing in which:

Figure 1 is a plan view showing my improved cup in its final form.

Figure 2 is a side view thereof in central vertical section illustrating the cup in its open form.

45 Figure 3 is a view showing the blank as it is produced by cutting off one corner of a square sheet of paper. The said corner being shown in dotted lines.

Figure 4 is a similar view of the blank showing, 50 by dotted lines thereon, the lines on which the wings of the blank are folded.

Figure 5 is a view showing the same blank partly formed into a cup by the first and second folds with the line of the third fold shown dotted 55 thereon.

Figure 6 is a view illustrating the manner in which a blank is cut from a web of paper and also showing the piece of waste which is trimmed from the blank in the same operation.

As shown (in Figure 3 of the drawing) the numeral 5 denotes the blank which consists simply of a square sheet of paper with one of the corners thereof (shown in dotted lines) cut off.

For the purpose of description, this blank may be said to comprise a body portion 7 and two 10 wing portions 8—8 as clearly illustrated in Figure 4 of the drawing. The wings are first folded on the body portion at the points indicated by dotted lines 9—9 into the form shown in Figure 5 of the drawing. It will be here seen that the wings 15 overlap each other in such a manner that they may be readily glued together in a suitable manner.

After the blank is in the form shown in Figure 5, the bottom portion thereof is folded back 20 at the point indicated by the dotted line 10 and also glued thereto, thus forming the completed cup shown in Figures 1 and 2 of the drawing. It will be noted that the wings 8, 8 overlap for a 25 distance below the folding point, on line 10, thus providing a seal for the bottom of the cup which will eliminate leakage.

The flap 11 provides a reinforcement for the cup, which makes possible the use of lighter weight paper with satisfactory results.

It is pointed out that by forming a cup from the blank as above described, the upper edges 13 of the wings 8—8 will be disposed below the rounded edge 14 of the body portion of the cup. This provides an advantage in the use of the cup 35 since interference by the user's nose during the drinking operation, will be avoided by means of the space provided between the said edge and the opposite edges 13 on the cup.

As illustrated in Figure 6 of the drawing, the 40 blank 5 may be cut from a web of paper 15 which is preferably supplied from a roll. This blank is cut off from the said web by a suitable cutting tool which also cuts off the corner 6 of the blank at the same time, thus completely forming the 45 blank 5 in one operation.

In order to reduce waste of material to a minimum, the blank is cut with its axis 16 at an angle of approximately 45° to the axis 17 of the web so that the sides of the web form two opposite 50 sides of the blank and the cutting off operation will form the other two opposite sides.

Adhesive material is applied to the web, as indicated at 18, before the blanks 5 are cut therefrom. This material is applied to the web in 55

an interrupted line in order to eliminate the presence of adhesive at the point where the blank is cut off.

After the blank is folded to the form shown in Figure 5, adhesive is applied as indicated at 19. The flap 11 is then folded over, on the line 10, and pressed down on the adhesive thus causing it to adhere to the side of the cup.

It will be readily understood from the above description, and from the drawing, that by means of the novel design of the cup described, it is made possible to produce a drinking cup from a blank extremely simple in form and which may be readily cut from a web, to which adhesive is previously applied, with a minimum amount of waste and folded into a cup having maximum rigidity.

By this invention applicant has also provided a cup which can be readily manufactured in an automatic machine that will produce the said cup from a web of paper; thus eliminating the necessary labor and waste which is required when the blanks are cut from a stack of sheets of paper as now commonly done in producing tapered cups.

While I prefer to cut off the corner 6 of the blank in order to provide a more attractive cup with a rounded edge 14, this corner may be left on the blank, if desired, thus rendering a simpler cutting-off operation and at the same time eliminating all waste of material.

I claim:

1. A paper cup comprising a blank having a point at the bottom thereof, side edges diverging from said point and opposite side portion fold-

ed into overlapping position upon the central portion of said blank on lines diverging from a point off the said blank and spaced from the bottom thereof.

2. A cup of the character described formed from a blank comprising a parallelogram having a corner portion thereof cut off, opposite corner portions folded back in overlapping position upon the central portion of said blank; the top edges of said overlapping corner portions being entirely disposed below the top edge of said body portion.

3. A blank for a cup of the character described comprising a substantially square sheet of material having its axis extending through two corners thereof; one of said corners being rounded and said blank being folded on lines diverging from a point in line with said axis which is off the said blank and spaced from that corner thereof which is opposite the said rounded corner.

4. A cup of the character described constructed from a blank of sheet material comprising a body portion having a lower portion terminating in a point at the bottom of said blank, side portions, the said side portions being folded into overlapping position upon the said body portion in a manner whereby the said lower portion of the body portion is exposed; said lower portion, together with the lower portion of each of said side portions, being folded upon said overlapping side portions and into contact therewith.

LOUIS V. LUCIA.
